(71) Applicant: **Roger McCollum**, Matamoras, PA (US)

* cited by examiner

(72) Inventor: **Roger McCollum**, Matamoras, PA (US)

Primary Examiner — Cynthia Ramirez
(74) *Attorney, Agent, or Firm* — Gold & Rizvi, P.A.; Glenn E. Gold

(**) Term: **14 Years**

(57) **CLAIM**
I claim the ornamental design for a skull-shaped positive crankcase ventilation valve, as shown and described.

(21) Appl. No.: **29/441,620**

DESCRIPTION

(22) Filed: **Jan. 8, 2013**

The patent or application file contains at least one drawing/photograph executed in color. Copies of this patent or patent application publication with color drawing(s)/photograph(s) will be provided by the Office upon request and payment of the necessary fee.

(51) **LOC (10) Cl.** **23-01**

FIG. 1 is a perspective top photographic image of a skull-shaped positive crankcase ventilation valve;

(52) **U.S. Cl.**

FIG. 2 is a perspective bottom photographic image thereof;

USPC **D23/233**

FIG. 3 is a front photographic image thereof;

(58) **Field of Classification Search**

FIG. 4 is a right side photographic image thereof;

USPC D23/233-237, 244-249; D11/117, 121,

FIG. 5 is a rear photographic image thereof;

D11/127, 128, 131.1, 136, 184; D9/626;

FIG. 6 is a left side photographic image thereof;

137/625.3, 625.31; 251/206, 207, 208

FIG. 7 is a top photographic image thereof; and,

See application file for complete search history.

FIG. 8 is a bottom photographic image thereof.

(56) **References Cited**

Color photographs are presented to properly present ornamental effects.
